UNITED STATES PATENT OFFICE.

GLENN F. COUCH, OF ROCHESTER, NEW YORK, ASSIGNOR TO THE SYMINGTON COMPANY, OF NEW YORK, N. Y., A CORPORATION OF MARYLAND.

DRAFT RIGGING.

Application filed February 7, 1925. Serial No. 7,622.

This invention relates to draft rigging for railway cars and more particularly to connecting means between the coupler and yoke member thereof whereby a desired amount 5 of angling therebetween is permitted.

One of the principal features of my invention, generally considered, is the provision of a key connected coupler and yoke with the key serving to transmit draft forces 10 therebetween and a shim seated on said key and formed so as to permit pivotal motion between said coupler and key, a swivel block also being provided between the butt of the coupler and a forward portion of the 15 yoke for permitting similar pivotal motion between the coupler, swivel block and yoke.

An object of the invention is to provide a swiveling or pivotal connection between the coupler and yoke members in railway 20 draft rigging in which a shim seated on a key connecting the coupler and yoke serves as a pivoting member instead of a pin extending entirely through the coupler.

Another object of the invention is the provision 25 of a pivotal connection between the coupler and yoke members in railway draft rigging in which a key serves to transmit draft forces between the coupler and yoke, and an intermediate swivel block formed 30 with a forwardly opening pocket, in which is seated the coupler butt, is provided between the coupler and yoke, the coupler and block being formed with interengaging faces for transmitting buffing forces from the coupler to the cushioning mechanism without 35 detriment to said block, said faces being adapted to permit pivotal motion between the coupler and block members.

A further object of the invention is the provision 40 of a swivel block or connecting member between the coupler and yoke in railway draft rigging, which member is formed to permit pivotal motion therebetween and is adapted to engage cushioning mechanism at the rear face thereof.

A still further object of the invention is the provision of a pivotal connection between a vertical yoke and coupler, said yoke being provided with side loops or walls

connecting forwardly extending arms thereof and serving to limit the pivotal motion of the coupler with respect thereto, a key passing through said loops and coupler and connecting the same for transmitting draft forces therebetween, a member seated on 50 said key and in a pocket of the coupler for permitting pivotal motion between the key and coupler, and another member between the coupler butt and cushioning means for transmitting buffing forces therebetween, 55 said member having bearing faces for permitting pivotal motion between it and the coupler as well as between it and the yoke.

The invention further consists in the construction of the several elements together 60 with their particular arrangement and combination as will become more apparent as the description proceeds.

In the drawings illustrating my invention, the scope whereof is pointed out in the 65 claims:

Figure 1 is a top plan view showing a coupler and yoke member connected in accordance with my invention.

Figure 2 is a side elevation of the embodiment of my invention illustrated in Figure 1, the yoke and key members being shown in vertical section.

Figure 3 is a transverse vertical section taken on the line 3—3 of Figure 1 and looking in the direction of the arrows.

Figure 4 is a view similar to Figure 1, parts, however, being shown in central horizontal section.

Figure 5 is a view similar to Figure 2, parts, however, being shown in vertical longitudinal section.

Figure 6 is a vertical longitudinal section of the coupler butt.

Figure 7 is a perspective view of the pivotal shim.

Referring to the drawings, in which similar reference characters designate corresponding parts in the several views, I have shown a coupler 1 connected to a yoke 2 by means of a key 3. The yoke 2 in the present embodiment is shown as of the vertical type, the forwardly extending arms 4

and 5 thereof being joined by loop portions or side walls 6 and 7. These side walls 6 and 7 are slotted at 8 and 9, respectively, for the passage of the key 3 therethrough, 5 and extend, one on each side of the coupler 1, for limiting pivotal motion thereof.

The coupler is provided with a slot 11 through which passes the key 3. The rearward portion of the slot 11 is enlarged to 10 form a pocket 12, said pocket being provided with rear faces formed as cylindrical bearing portions 13, 14 and 15.

A shim 16, shaped to accurately fit into the rear portion of the pocket 12 and formed 15 with correspondingly curved bearing portions 17, 18 and 19 for pivotal engagement with respect to the coupler bearing portions 13, 14 and 15, is provided and seated in said coupler pocket 12, as illustrated most clearly 20 in Figures 4 and 5. The forward face 21 of the shim 16, when positioned in the coupler pocket, is substantially flat except where a bearing pocket 22 is provided for engagement with respect to the key member 25 3. It will be noted that it is necessary to first insert the shim 16 in place in the pocket 12 of the coupler and when the key 3 is passed through the slot 11 therein it 30 serves to lock the shim in place and prevent loss thereof while the parts are assembled.

The rear face or butt portion of the coupler 23 is curved co-axially with respect to the curved portions 13, 14 and 15 of the pocket 12 therein. This curved outer portion of the 35 coupler fits into and engages with a swivel block or auxiliary member 24 between the coupler 1 and yoke 2. This member 24 is provided with a co-axially curved bearing portion 25 into which the butt of the coupler 40 fits and bears against.

The auxiliary member or swivel block 24 is provided with forwardly extending arms 26 and 27. The arm 26 is provided with an upwardly extending curved flange 28 and the 45 arm 27 has a similarly curved flange 29 extending downwardly therefrom. These flanges are co-axially curved with respect to the bearing portion 25 and are arranged adjacent the front edges 31 and 32, respectively, of the forwardly extending arms 4 and 5 of the yoke 2. These edges 31 and 32 are curved axially with respect to the flanges 28 and 29 so that pivotal motion between the auxiliary member or swivel block 24 and 55 the yoke 2 is permitted. The rear face 33 of the swivel block 24 is preferably substantially flat and adapted for engagement with cushioning mechanism illustrated diagrammatically by dot and dash lines.

60 It will be evident that by virtue of the aforescribed construction, a strong and easily manufactured pivotal connection between the coupler and yoke members in railway draft rigging is provided as the shim 65 16 permits pivotal motion between the cou-

pler 1 and the key member 3 in a substantially horizontal plane by virtue of the engaging cylindrical bearing faces 13, 14 and 15 with 17, 18 and 19, respectively.

When draft forces are applied to the coupler such forces are transmitted first to the shim member 16, then to the key 3, and through said key to the wall portions 6 and 7 of the yoke. When buffing forces, however, are applied to the coupler the key is relieved 75 of substantially all strains because such buffing forces are transmitted to the swivel block or auxiliary member 24 and from there to the engaging cushioning mechanism. By reason of the pivotal relation between the 80 coupler butt and the service block, a flat and substantially transverse force is always presented to the cushioning mechanism for the efficient transference of buffing forces thereto. Even though the coupler pivots, 85 it always, in effect, presents a flat face squarely to the cushioning mechanism. It will be noted that on the application of buffing forces it is not intended that the front edge of the key should be engaged by 90 the forward end of the slot 11. The key, however, at all times serves to support the coupler, yoke and auxiliary member in horizontal alinement, as will be understood.

On account of the coupler 1 being formed 95 to pivot with respect to the swivel block 24, which is likewise shaped for pivotal motion with respect to the yoke 2, a certain amount of the pivotal motion between coupler and yoke may occur between the coupler and 100 swivel block and the rest between the swivel block and yoke, as will be obvious. If the motion between the coupler and swivel block is in the opposite direction from that 105 between the swivel block and coupler, a transverse or lateral motion of the coupler butt between the side walls 6 and 7 of the yoke, may be effected.

Having now described my invention, what I claim is:

1. In a railway draft rigging, the combination with a coupler having a curved bearing face on the rear end thereof, of a yoke, means extending through said coupler and yoke for transmitting draft forces therebetween, a shim between said coupler and transmitting means permitting pivotal motion therebetween, cushioning mechanism, and an auxiliary member between the rear end of the coupler and the cushioning mechanism, presenting a flat face to the cushioning mechanism and a curved cooperating bearing face to the bearing face on the coupler. 115

2. In a railway draft rigging, the combination with a coupler, of a yoke, a cushioning means within said yoke, means extending through said coupler and yoke for transmitting draft forces therebetween, a 120 shim between said coupler and transmitting 130

means permitting pivotal motion therebetween, and a swivel block between said coupler and yoke for transmitting buffing forces to said cushioning means and permitting 5 pivotal motion between the coupler and yoke.

3. In a railway draft rigging, the combination with a slotted coupler, of a slotted yoke, cushioning mechanism embraced by 10 said yoke, a key adapted to pass through said slots between said coupler and yoke, a shim seated in said coupler and both provided with correspondingly curved cooperating bearing faces for pivotal motion therebetween, said shim engaging the key and both shim and key provided with correspondingly curved cooperating bearing faces, and an auxiliary member between said coupler and cushioning mechanism, the engaging faces of the member and coupler being formed as bearings coaxial with the bearing faces on the shim.

4. In a railway draft rigging, the combination with a slotted coupler, of a slotted yoke, a key adapted to pass through said slots, a shim seated in said coupler and both shim and coupler provided with correspondingly curved co-operating bearing faces permitting pivotal motion therebetween, said 20 shim also engaging the key and both provided with corresponding bearing faces, and a swivel block between said coupler and yoke allowing pivotal motion therebetween.

5. In a railway draft rigging, the combination with a slotted coupler, of a slotted yoke, a key adapted to pass through said slots for connecting said coupler and yoke, a shim seated in said coupler and both provided with curved bearing faces permitting 35 pivotal motion therebetween, said shim also engaging the key and both provided with co-operating bearing faces, and a swivel block between said coupler and yoke and provided with curved cooperating bearing faces engaging 40 similar bearing faces on said coupler and yoke for permitting pivotal motion between said coupler, swivel block and yoke.

6. In a railway draft rigging, the combination with a slotted coupler, of a slotted yoke, a key adapted to pass through said slots to connect said coupler and yoke, a shim seated in a pocket in said coupler and formed with a curved cooperating bearing face engaging a similarly curved bearing face in 50 said pocket for pivotal motion therebetween, said shim also engaging the key, and a swivel block between said coupler and yoke, said swivel block being formed with a curved bearing face for pivotal motion with respect 55 to the coupler.

7. In a railway draft rigging, the combination with a coupler, of a yoke, means extending through said coupler and yoke for transmitting draft forces therebetween, a 60 shim member between said coupler and

transmitting means permitting pivotal motion therebetween, and a swivel block between said coupler and yoke for permitting pivotal motion therebetween, said swivel block having a rear face adapted to engage 70 cushioning mechanism.

8. In a railway draft rigging, the combination with a slotted coupler, of a slotted yoke, a key passing through said slots and connecting said coupler and yoke, a curved 75 shim seated in said coupler and on said key and permitting pivotal motion with respect to said coupler and shim, a swivel block between said coupler and yoke, said swivel block and coupler being both provided with 80 correspondingly curved cooperating bearing faces for pivotal motion therebetween, and correspondingly curved cooperating bearing faces also provided on the swivel block and yoke for similar motion between said block 85 and yoke, said block having a rear substantially flat face adapted for engagement with cushioning mechanism.

9. In a railway draft rigging, the combination with a slotted coupler having a 90 curved butt portion, of a slotted yoke, a key passing through said slots and connecting said coupler and yoke, and a swivel block with a curved bearing pocket embracing the curved butt of the coupler for pivotal motion 95 therebetween.

10. In a railway draft rigging, the combination with a coupler having a curved butt portion, of a yoke with forwardly extending 100 arms with curved front edges, a key connecting said coupler and yoke, and a swivel block with a convex bearing pocket embracing the curved coupler butt for pivotal motion therebetween, said block having forwardly extending arms provided with an upwardly and a downwardly projecting flange, 105 respectively, said flanges being curved to cooperatively embrace the curved front edges of the yoke.

11. A coupler provided with a butt portion formed with a rear wall, the outer face of which is formed as a cylindrical bearing for pivotal motion with respect to a yoke and slotted for being connected to said yoke by means of a key and providing bearing 110 portions for said key.

12. A coupler provided with a butt portion, the rear wall of which is curved as a cylindrical bearing for pivotal motion with respect to a yoke and formed with a pocket 120 in the stem thereof, the inner face of said pocket being coaxially curved with respect to the rear wall for engagement with a correspondingly curved shim and slotted for receiving a connecting key which is also adapted to lock said shim in place.

13. A yoke formed with a four-walled forward end, two opposite walls being slotted to receive a key and the other two walls being formed with cylindrical edges for per- 130

mitting pivotal engagement with respect to a coupler.

14. A yoke provided with a four-walled integral construction at its forward end joining forwardly extending arms thereof, two opposite walls being slotted for the reception of a horizontal key for joining said yoke to a

coupler, and the other two walls being formed at the forward edges thereof with co-axially curved bearing portions for horizontal pivotal movement with respect to the coupler. 10

In testimony whereof I affix my signature.
GLENN F. COUCH.
